UNITED STATES PATENT OFFICE.

ORLANDO V. FLORA, OF MADISON, INDIANA, ASSIGNOR TO HIMSELF AND
JOHN G. MOORE, OF SAME PLACE.

IMPROVEMENT IN CARPENTERS' VISSES.

Specification forming part of Letters Patent No. 57,250, dated August 14, 1866.

To all whom it may concern:

Be it known that I, ORLANDO V. FLORA, of Madison, in the county of Jefferson and State of Indiana, have invented an Improved Vise; and I do hereby declare that the following is a full and exact description thereof, reference being had to the accompanying drawings, making part of this specification—

Figure 1 being a side elevation of a wood or carpenter's vise as improved by me; Fig. 2, a rear view thereof, the bench being shown in vertical section; Fig. 3, a view representing the invention as modified for an iron vise.

Like letters designate corresponding parts in all of the figures.

Let A represent a carpenter's bench, B the stationary jaw of the vise attached to the bench, and C the movable jaw of the vise. The beam D has cut, for a few inches on its rear end, a screw-thread, n, which turns in a nut, F, simply for tightening the jaws against the article to be clamped. The principal movement of the movable jaw C—in and out—is effected simply by sliding backward and forward the beam D, moving freely through the stationary jaw.

In order to keep the beam in its proper horizontal position the nut F has two side projections, f, f, which slide in ways a, a of the bench, as shown in Fig. 2.

A brace, I, extends from near the lower end of the movable jaw C, where it is attached thereto, backward and upward through a vertical slot in the stationary jaw to the nut F, or to a block, i, attached thereto, being pivoted or otherwise secured to said block or nut, as at m, Fig. 1. This keeps the movable jaw always in a position parallel, or nearly so, with the stationary jaw.

My present improvement consists in the employment of a ratch-bar, G, under the beam, secured to the nut F at the rear end, while its front end enters and slides in the movable jaw C. The teeth g, g of this ratch hold upon a fixed catch, H, firmly attached to the stationary jaw B, substantially as represented, and

thus the movable jaw is held from moving away farther from the stationary jaw, in whatever position the ratch may be placed.

In order to slide the beam and movable jaw in or out the outer end of the beam is simply first raised (the beam-aperture through the stationary jaw being enlarged vertically enough for the purpose) till the ratch-teeth are disengaged from the catch, and then the beam can be directly moved in or out to any extent without hindrance. Then, when the outer end of the beam is dropped, the ratch G hooks on the catch H again, and holds the movable jaw to that position. When the jaw is by this means brought up to an article to be clamped a turn or two of the beam causes the screw n to tighten the jaw firmly against the article.

To unclamp, the screw is first reversed till the article is loosened, and then the beam is free to be moved in or out, as above described.

Fig. 3 shows the vise as modified for iron-work. Here the stationary jaw B has a suitable flange, P, to secure it upon the top of the bench by screws t, and there is a slot, R, therein, in which a guide-pin, S, with a head, r, slides to keep the ratch G in place. In this case the beam does not extend back over the ratch, but the ratch-bar forms the beam proper, and its front end bends upward to form a nut, F, the movable jaw C being pivoted to it, as at g. There is then a mere tightening-screw, D, where the beam would be in the wood vise. No brace to preserve the parallelism is here needed.

What I claim as my invention, and desire to secure by Letters Patent, is—

The combination of the fixed catch H and the ratch-bar G, movable up and down to clear and engage with the catch, substantially as and for the purpose herein specified.

The above specification of my improved vise signed by me this 1st day of June, 1866.

ORLANDO V. FLORA.
